UNITED STATES PATENT OFFICE

LEVI D. HOUGHTALING, OF READING, PENNSYLVANIA

SILO STAVE

Application filed September 30, 1930. Serial No. 485,496.

This invention relates to a stave construction designed particularly for use in constructing silos of the type disclosed in my United States Patent No. 1,750,600, although 5 I do not limit myself to its use therein.

An object of this invention is to provide a stave of a simple but durable structure, and having means for its quick assembly into its final position.

10 A further object is to avoid the necessity of costly bricklaying in the construction of silos, the staves herein described and claimed being easily assembled by one having little or no experience.

15 Still a further object of this invention is to provide a silo stave comprising a concrete body having a reinforcing framework embedded therein, said framework comprising means whereby said stave may be interlocked 20 with adjacent staves when set up in a building structure.

Other objects and advantages will appear in the following specification, and the novel features of the invention will be particularly 25 pointed out in the appended claims.

My invention is illustrated in the accompanying drawings, forming part of this application, in which

Figure 1 is a perspective view of a silo 30 constructed in accordance with my invention,

Figure 2 is a perspective view of one of my improved staves,

Figure 3 is a side elevation of a row of my 35 improved staves connected together to form, for example, the wall of a silo such as is shown in Figure 1,

Figure 4 is a longitudinal sectional view, partly broken away, of a pair of my staves in assembled position, and portions of abutting 40 staves,

Figure 5 is a partial sectional view taken on line 5—5 of Figure 4,

Figure 6 is a perspective view of a horizontal reinforcing member hereinafter more 45 fully described, and

Figure 7 is a fragmentary perspective view showing the reinforcing elements.

Referring more particularly to the drawings, 10 indicates the body of a stave. It will 50 be seen that the outer or exposed face 11 of the

stave has a projecting edge 12 which extends lower than its adjacent edge 13. It will further be seen that the inner face 14 of the stave has a projecting edge 15 which extends higher than its adjacent edge 16. Vertically disposed and permanently embedded in the stave is a pair of tubular steel reinforcing members 17. These members 17 extend from a pair of cone-shaped openings 18 in the edge 16 through the edge 12, and have free ends 19 at their lower extremities. The free ends 19, it will be seen, are adapted to fit into the cone-shaped openings 18 of the subjacent stave. Also permanently embedded in the body of the stave and spot-welded to the members 17 is a series of horizontal reinforcing members 20, of which I have shown three in my preferred form.

Locking sockets 21 are permanently affixed to one end of the members 20.

These members 20 extend from the socket 21 and protrude from the other side of the stave. The protruding ends are formed into keys 22. The locking sockets 21 are adapted to receive the keys 22 of the adjacent stave, when assembled. It will be noted that the hollow members 17 are adapted to act as drains for any seepage that may accumulate between a stave and its overlying stave, thus forming a continuous vertical drainage system for any structure that might be erected by the use of said staves.

When a circular structure, such as that shown in Figure 1 is built with my improved staves, the completed structure is braced against outward strain by encircling steel bands 23, which are more particularly described in my above-mentioned patent.

It will be seen from the above that my stave may be quickly assembled into a wall by first, forming a bottom row of staves, and there assembling the remainder of the staves until a desired height is reached.

This is done by attaching the free ends 19 in any suitable manner to a concrete base, then inserting the keys 22 of the adjacent stave in the sockets 21 of the first stave. After the bottom row has thus been formed, all that is necessary is the placing of the free ends 19 in the cone-shaped openings of the

underlying stave, at the same time placing the keys 22 in the sockets 21 of the adjacent stave. The hollow tubes together with the cone-shaped openings 18 will serve to drain 5 off any accumulation of liquid which may collect between any stave and its overlying stave.

The horizontal bars 20, together with the vertical bars 17, by means of the welded joint 10 securing them together, form a rigid reinforcing framework for the stave or block. In addition to the reinforcing feature, this framework provides the means whereby the interlock is formed with adjacent staves, thus 15 having the advantage of performing a double function in this organization.

What I claim is:

1. A stave for building purposes comprising a concrete body, having a stepped top and 20 stepped bottom, hollow vertical reinforcing members which protrude at the bottom, cone-shaped openings in the top arranged to receive the protruding ends of the vertical members of the overlying stave, having horizontal reinforcing members spot-welded to 25 the vertical members and projecting from one side of the body to form a key and having sockets formed at the other end arranged to receive the keys of the adjacent stave.

30 2. A stave for building structures comprising a concrete body having stepped top and bottom faces, hollow vertical reinforcing members embedded in said body, inset from one end to form a socket therein, and projecting from the other end thereof, to permit 35 said projecting portion to extend into the socket portion of a subjacent stave, said hollow vertical reinforcing members providing means whereby a continuous hollow drain- 40 ing passageway is formed when said block is placed in operative position in a building structure.

3. A reinforcing and interlocking member 45 for a concrete building block construction comprising an elongated shank, an enlarged head at one end thereof, a socket at the other end thereof, said socket having an enlarged portion adapted to receive the enlarged head of an adjoining reinforcing member of a contiguous concrete block, said socket having a 50 reduced portion formed therein adapted to engage the shank of the adjoining member of a contiguous concrete block, said enlarged and reduced socket portions forming means 55 whereby said enlarged head is locked against movement when said reinforcing and interlocking member is operatively embedded in a building block construction.

60 4. A building block for concrete structures comprising a concrete body, a rigid framework permanently embedded in said body, said framework comprising means adapted to interlock with adjacent blocks at all contacting faces when said block is operatively 65 placed in a building structure.

5. A building block for concrete structures comprising a concrete body, a rigid framework permanently embedded therein, said framework comprising a series of longitudinal members and a series of transverse members, said members being permanently secured to each other, said framework providing means whereby an interlock with adjacent blocks is adapted to be effected when the block is placed in operative position in a 75 building structure.

6. A building block for concrete structures comprising a concrete body, a reinforcing framework embedded therein, said framework providing means whereby sockets are 80 formed on two adjacent faces of said block and studs are formed on the correspondingly opposite adjacent faces of said block, said sockets and studs forming means for interlocking said block with adjacent blocks when 85 placed in operative position in a building structure.
